(57) **CLAIM**

The ornamental design for plumbing faucet with shower tube, as shown and described.

DESCRIPTION

FIG. 1 is a perspective view of a plumbing faucet with shower tube according to the invention;

FIG. 2 is a side view thereof, with the opposite side view being a mirror image of FIG. 2;

FIG. 3 is a top view thereof;

FIG. 4 is a bottom view thereof;

FIG. 5 is a rear view thereof;

FIG. 6 is a front view thereof;

FIG. 7 is a second perspective view thereof, with the shower tube moved into an extended position;

FIG. 8 is a second side view thereof, with the shower tube in the extended position; the opposite side view with the shower tube in the extended position being a mirror image of FIG. 8

FIG. 9 is a top view thereof, with the shower tube in the extended position;

FIG. 10 is a bottom view thereof, with the shower tube in the extended position;

FIG. 11 is a rear view thereof, with the shower tube in the extended position; and,

FIG. 12 is a front view thereof, with the shower tube in the extended position.

The broken lines in the Figures are for illustrative purposes only and form no part of the claimed design.
